[57] CLAIM

The ornamental design for a connection piece for milk pipeline valve, as shown and described.

DESCRIPTION

FIG. 1 is a lower front right perspective view of a connection piece for milk pipeline valve in accordance with the present invention;

FIG. 2 is an upper left rear perspective view thereof;

FIG. 3 is a rear view thereof;

FIG. 4 is a bottom plan view thereof;

FIG. 5 is a left side elevational view thereof;

FIG. 6 is a front view thereof;

FIG. 7 is a top plan view thereof;

FIG. 8 is an inverted right side elevational view thereof;

FIG. 9 is a lower front right perspective view of the exchangeable upper part of the connection piece which is a component of the connection piece shown in FIGS. 1-8 hereof;

FIG. 10 is an upper rear left perspective view thereof;

FIG. 11 is a rear elevational view thereof;

FIG. 12 is a bottom plan view thereof;

FIG. 13 is a left side elevational view thereof;

FIG. 14 is a front elevational view thereof;

FIG. 15 is a top plan view thereof; and,

FIG. 16 is an inverted right side elevational view thereof.
